2 SHEETS—SHEET 2.

UNITED STATES PATENT OFFICE.

HERMAN F. ROSENCRANS, OF DURAND, MICHIGAN.

VALVE.

1,143,999.

Specification of Letters Patent. Patented June 22, 1915.

Application filed August 16, 1912. Serial No. 715,521.

To all whom it may concern:

Be it known that I, HERMAN F. ROSENCRANS, citizen of the United States, residing at Durand, in the county of Shiawassee and 5 State of Michigan, have invented certain new and useful Improvements in Valves, of which the following is a specification.

My invention relates to new and useful improvements in valves and operating mechanism therefor and more particularly to valves of the balance type for use in high pressure water supply mains and particularly in connection with a water supply system such as that covered by my copending 15 application filed August 16, 1912, and bearing the Serial No. 715,522.

The primary object of my invention is to provide a cutoff valve for high pressure water mains which will be practically balanced in its action, requiring but little force to either open or close the valve.

A further object of my invention is to provide a valve in which the movable part need be moved only through a slight distance to fully open the valve. And a still further object of my invention is to provide a valve of the above described type in which the movable part comprises a hollow cylindrical valve mounted for reciprocation in 30 the valve casing and a simple linkage for reciprocating said valve, thereby providing a ready means for mechanically opening and closing the valve so that the passage of water through the same may be automatically governed.

With these and other objects in view, my invention will be more fully described, illustrated in the accompanying drawing, and then specifically pointed out in the claims 40 which are attached to and form a part of this application.

In the drawing: Figure 1 is a central longitudinal section taken through the valve casing and valve, showing the valve operating linkage in elevation; Fig. 2 is a top plan view of the valve proper, showing the valve stem in section; Fig. 3 is a central longitudinal sectional view, showing an elbow valve and casing constructed in accordance 50 with my invention; Fig. 4 is a section on the

line 4—4 of Fig. 3, looking in the direction of the arrows; Fig. 5 is a central longitudinal sectional view of a further modified form of my valve, showing the same employed as a straightaway valve; Fig. 6 is 55 an end elevation of the valve shown in Fig. 5, showing the operating mechanism of the valve.

Corresponding and like parts are referred to in the following description and indicated 60 in all the views of the drawings by the same reference characters.

The valve casing, which may be of any preferred type and of any suitable metal, is designated as a whole by the numeral 10 and 65 is constructed along the general lines of the common type of globe valve casing, said casing including a body portion 11 hollowed to form a central valve chamber 12 which is divided transversely adjacent its central 70 portion by a web 13, and end portions 14 and 15 adapted for connection with the pipes of the water main and having inlet and outlet passages 16 and 17, respectively, the former of which communicates with that portion of 75 the central valve chamber 12 above the web 13, while the latter leads from that portion of said chamber below the web.

The central valve chamber 12 extends by its ends through the top and bottom of the 80 valve casing and the top of the valve casing surrounding said chamber is provided with a threaded flange 18 adapted to receive a bonnet 19 closing the upper end of the valve casing, a suitable packing ring 20 being 85 preferably interposed between the valve casing and bonnet. The bottom of the valve casing is provided with a downwardly directed flange 21, the edge of which is plane surfaced and the open lower end of the chamber 12 is closed by a valve seat 22 having a peripheral flange 23 for engagement against the flange 21, a packing ring 24 being 90 preferably interposed between said flanges, the valve seat being secured in place by a plurality of bolts or other suitable fastenings 25 passed through the flange 23 of the valve seat and into the flange 21 of the valve casing.

As shown, the central valve chamber 12, 100

- immediately above and below the web 13, is enlarged to permit the free passage of water through the valve. The valve seat proper is formed by a semi-spherical extension 26 integrally connected with the body portion 22 by a reduced neck 27, said valve seat proper being so formed as to extend upwardly within the enlarged lower end of the central chamber of the valve casing with its 5 plane surface uppermost and disposed in a horizontal plane. It will therefore be seen that when the valve proper is raised from engagement with the upper face of the valve seat 26, water passing through the valve seat 26, cannot only flow directly to the outlet passage 17, but can also flow to said passage indirectly through the annular space or chamber 28 between the body portions 22 and 26 of the valve seat.
- 10 The valve which I employ in this valve casing consists of a hollow cylindrical valve 29 fitting in the central portion of the valve chamber 12 and engaging by its outer face against the side walls of the web 13 in such 15 a manner that when seated by its lower edge upon the upper face of the valve seat, all passage of water from the upper portion of the valve chamber 12 to the lower portion thereof is cut off. This cylindrical valve is 20 provided at its upper and lower ends with spiders 30 by means of which it is mounted upon a valve stem 31, the lower end of which seats in a socket 32 formed centrally in the valve seat and the upper end of which extends through a stuffing box in the bonnet 19 and beyond the end of the bonnet. The valve seat is preferably provided in its valve receiving face with an annular groove in which is seated a packing ring 33 upon 25 which the valve bears when in closed position and the socket 32 is so proportioned that when the valve is in closed position, the lower end of the valve stem extends nearly to the bottom of the socket while, 30 when the valve is in open position, the lower end of the valve stem still seats in the upper portion of the socket.
- 35 The upper edge of the valve 29 is preferably beveled internally as shown at 34 to offer less resistance to the passage of the water through the valve and also to decrease the effective area offered by the valve to water pressure and tending to prevent the opening of the valve. As will be readily 40 seen, this valve is practically of the balance type and but little force is required to open the valve or to hold the valve when in open position.
- 45 The upper end of the valve stem 31, which projects beyond the bonnet, is provided with a laterally directed, longitudinally bored head 35 and pivotally connected to this head by a bolt 36 is a link 37, the free end of which is pivotally connected by a second bolt 50 55 60 65 70 75 80 85 90 95 100 105 110 115 120 125 130 135 140 145 150 155 160 165 170 175 180 185 190 195 200 205 210 215 220 plane to seat the valve 50. It will be readily apparent that when the valve is raised from engagement with the valve seat, a free circulation of water past the valve seat is provided by the enlarged portion 64 of the valve chamber 44.

In Fig. 5 of the drawings, I have illustrated a still further modification of my invention showing my valve employed in connection with a straightaway valve. In this form, the valve casing 65 is substantially cylindrical in shape being bulged somewhat as shown at 66 to provide an enlarged portion 67 of the longitudinally extending passage 68. This passage is slightly reduced intermediate its length as shown at 69 to form a bearing for the valve proper 70, this valve being identical in construction with the valves 29 and 50 above described. The valve seat 71 is also identical in construction with the valve seat 58 of the valve shown in Fig. 3 and is secured in like manner by studs or pins 72 which in this case are threaded by one end into the valve seat and by their opposite ends into the ears 73 of the ring 74. This ring is seated between the annular flange 75 of the valve casing and the corresponding flange 76 of the outlet pipe 77 and the valve seat is therefore properly maintained in position. The inlet end of the valve casing is thickened and plane faced as shown at 78 to provide a seat for the flanged end 79 of the inlet pipe 80, the flanges 79 and 78 being secured together by bolts or other suitable fastening devices.

As will be apparent, the valve stem 81 of this valve extends longitudinally and centrally of the valve casing and in alinement with the axes of the inlet and outlet pipes. The free end of the valve stem is pivotally connected to a link 82 and the free end of this link is in turn connected to a crank arm 83 carried by a shaft 84. This shaft 84, as best shown in Fig. 6 of the drawings, extends through the valve casing being mounted for rotation in suitable bearings 85 formed upon the valve casing and is extended at one end to receive an operating lever 86 by means of which the valve may be opened and closed.

It will be apparent that the valves shown in Figs. 3 to 6 inclusive are merely somewhat altered embodiments of the principles illustrated in the valve construction of Fig. 1, the valve in all cases being identical and operating in the same manner.

It will of course be understood that the valve stem in the form shown in Figs. 1 and 3 may, if desired, be threaded to engage with threads formed in the bonnet and the valve therefor operated by means of a hand wheel. In fact I do not wish in any way to limit myself to the specific structure illustrated and described as various minor

changes in details of construction may be made at any time without departing from the spirit of my invention.

As shown, the upper end of the valve is flared to provide a beveled inner face and an outwardly inclined outer face which seats upon the beveled upper face 29' of the web. By beveling the upper face of the valve inferiorly in this manner, the direct pressure of the water upon the valve is reduced and at the same time a firmer and closer seating of the valve against the web is obtained.

Having thus described the invention, what is claimed as new is:

1. A valve including a valve casing having a valve chamber divided by a transversely extending web provided with a valve passage, one end of said valve chamber extending through the casing to form an outlet passage, a ring secured to the outer face of the casing about said outlet passage and provided with inwardly directed ears, studs secured to the ears and extending inwardly of the valve chamber, a valve seat carried by said studs, and a hollow cylindrical valve movable in the valve passage and adapted for engagement with the seat.

2. A valve including a substantially cylindrical valve casing reduced intermediate its length to form a valve passage and enlarged adjacent the passage to form a chamber having a discharge passage leading through the valve casing, a seat supported centrally of said chamber, a hollow cylindrical valve movable in the valve passage and adapted to engage by one end against the valve seat, and means for reciprocating said valve, said means including a valve stem carried by the valve, a shaft journaled through the valve casing and carrying a crank arm, and a link pivotally connecting the crank arm and free end of the valve stem.

3. A valve including a valve casing having a valve chamber divided by a transversely extending web provided with a valve passage, one end of said valve chamber extending through the casing to form an outlet passage, a ring secured to the outer face of the casing about said outlet passage and provided with inwardly directed ears, studs secured to the ears and extending inwardly of the valve casing, a valve seat carried by said studs, and a hollow cylindrical valve movable in the valve passage for engagement with the seat, one end of said valve being flared for simultaneous engagement with the web.

4. A valve including a valve casing having inlet and outlet passages enlarged into chambers at their inner ends, a web dividing the casing between the chambers and provided with a central passage, a valve seat supported in spaced relation to the web and substantially centrally of the outlet cham-

ber, the space between the web and seat being entirely unobstructed, as well as the space surrounding the seat, and a hollow cylindrical valve open at its ends reciprocally mounted in the passage of the web and movable into and out of engagement with the seat.

In testimony whereof I affix my signature in presence of two witnesses.
